DOUBLE OVEN

Peter L. Helgeson, Allentown, Pa., assignor to Caloric Corporation, Topton, Pa., a corporation of Pennsylvania

Filed Apr. 20, 1965, Ser. No. 84,888

Term of patent 14 years

(Cl. D81—4)

FIG. 1 is a front elevational view of a double oven embodying my new design.

FIG. 2 is a perspective view of the same.

FIG. 3 is a fragmentary side elevational view of the same.

FIG. 4 is a fragmentary top plan view of the same.

The parallel-line and grid-line textures on the front surface of the stove represent contrast.

I claim:

The ornamental design for a double oven, as shown and described.
